(57) **CLAIM**

The ornamental design for a cosmetic container, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a cosmetic container showing my new design;

FIG. 2 is a front view of the cosmetic container shown in FIG. 1;

FIG. 3 is a rear view of the cosmetic container shown in FIG. 1;

FIG. 4 is a left side view of the cosmetic container shown in FIG. 1;

FIG. 5 is a right side view of the cosmetic container shown in FIG. 1;

FIG. 6 is a top view of the cosmetic container shown in FIG. 1;

FIG. 7 is a bottom view of the cosmetic container shown in FIG. 1;

FIG. 8 is a referential perspective view thereof shown in a closed position of use;

FIG. 9 is a referential front view of the cosmetic container shown in FIG. 8;

FIG. 10 is a referential rear view of the cosmetic container shown in FIG. 8;

FIG. 11 is a referential left side view of the cosmetic container shown in FIG. 8;

FIG. 12 is a referential right side view of the cosmetic container shown in FIG. 8;

FIG. 13 is a referential top view of the cosmetic container shown in FIG. 8; and,

FIG. 14 is a referential bottom view of the cosmetic container shown in FIG. 8.
